MANUFACTURE OF WIRE COILS

Isabelle M. Sobierajski, St. Marys, Pa., assignor to Sylvania Electric Products, Inc., a corporation of Delaware
Filed Nov. 25, 1960, Ser. No. 71,730

4 Claims. (Cl. 29—423)

This invention relates to the manufacture of fine coiled wires such as are used as heaters in electron tubes or filaments in incandescent lamps.

In the process of making heaters for electron discharge devices, it is common practice to wind the heater on a mandrel to form a wire coil and then to coat the coil with insulating material. When the wire is heavy enough to permit, the coil winding mandrel is removed mechanically before coating. When the coil wire used is too fine to support its own weight, mechanical removal of the mandrel is not practical and the procedure has been to coat the heater while the mandrel is still inside the coil followed by sintering of the coating, and then selectively dissolving the coil supporting mandrel by the use of acids, thus leaving only the coated heater coil. Similarly, where a coiled coil of wire of the type often used as a filament for a lamp has been manufactured, it has been the practice to coil the filament about a mandrel, coil the coiled wire and mandrel into a spiral, cut off sections of the spiral so as to form segments, drop the coil of segments into a vat and dissolve out the mandrel. In both of these instances, the metal of the mandrel and of the wire coiled about the mandrel was chosen to be selective to the action of the acid bath so that only the mandrel would be dissolved out. For example, the mandrel may be molybdenum; the wire coiled about the mandrel may be tungsten and the acid bath may consist of 40 parts concentrated sulphuric acid, a like proportion of concentrated nitric acid and twenty parts of water.

Where very fine wire heaters are so manufactured, that is, where the cut off segments or sections of spiral are dropped into a common acid vat, it has been found that the coils become entangled, and attempts to separate the coils after mandrel removal result in destruction of the coating on the heaters or permanent deformation of the coils, with resultant loss of manufactured products.

It is, therefore, an object of this invention to avoid entanglement of the very fine wire coils during the mandrel dissolving operation.

In carrying out this invention, the segments of coiled heaters or filaments, as they are severed from the spiral or string, drop into vials, one for each heater. The vials are of a size which comfortably erectly accommodate the individual heaters or filaments. Within the vials is the acid mixture for dissolving out the mandrel. After the mandrel has been removed, the acid in the vials is replaced by clear water to wash the segments constituting the heater or filament.

In order to give a clearer understanding of the invention, attention is directed to the following description and accompanying drawings in which:

FIGS. 1 and 2, in diagrammatic form, illustrate apparatus for carrying out the process;

FIG. 3 illustrates, in diagrammatic form, an automatic apparatus for carrying out the process; and

FIG. 4 illustrates a plan view of a compartmented tray with coil segments in some of the compartments.

Referring to FIGS. 1 and 2, after the wire and mandrel have been coiled into a string 10, in conventional fashion, the segment of filament or heater 12 and mandrel 13 is cut off from the string by cutting knives 14 and 16 and allowed to drop into a vial or glass tube 18. This vial is provided with a hole 20 in or immediately above the bottom of the vial so as to permit free transfer of liquids

2

therethrough. The hole 20, is, of course, small compared to the diameter of the segment to prevent the segment from falling out of the vial and it is placed close to the bottom or in the bottom to allow proper draining of fluids from the vial and to prevent the coil segment from snugly fitting near the upper end of the vial.

As each vial 18 is loaded with a coil segment 12 and mandrel 13, it is inserted into a beaker or vat 22 preferably provided with a drain valve 24 and valve controlled inlet pipes 26 and 28 for the admission of acid or rinse water to the vat, as desired. The vat or beaker 22 is initially filled with acid 23 which enters the individual vials 18, after they have been placed in the vat, through the openings 20 and filling the vials to the same level as the level of the acid in the vat. The acid then acts, selectively, to dissolve out the mandrel 13, thereby leaving the fine coil of wire intact, self supporting, and without entanglement with adjacent coils.

After the acid dissolving action has been completed, the vat is drained and the acid is replaced by clear water. If desired, a hose or hoses may be attached to the water pipe and lead directly into the vials 18 to facilitate the washing operation. If hoses are not used, as many fillings and emptyings of the vat may be employed as desired.

The segment 12 may be formed from tungsten and mandrel 13 may be molybdenum while the acid bath may comprise the nitric and sulphuric acid solution mentioned above. Segments 12 can be coated with an insulating coating before or after removal of mandrel 13, as desired.

In FIG. 3 there is diagrammatically shown an automatic mechanism for loading the vials with segments, such as individual heaters. An electric motor 30 drives a Geneva drive 32 to periodically rotate a shaft 34 one revolution for each output operation of the gearing in the Geneva drive mechanism. The shaft, through suitable speed reducing gearing 36, 38, drives a shaft 40 mounted for rotation in fixed bearings 42 and 44 and having a split lower end 46 to straddle the upper keyed end 48 of a shaft 50. The shaft 50 serves as part of a vial holder 49 of acid resistant material. The holder comprises the shaft 50 and two circular discs 52 and 54 fastened to the shaft. The upper circular disc 52 is fairly thick and provided with equally spaced openings therethrough near the periphery of the disc to snugly and slidably accommodate the vials so that the vials may remain upright in the holder and rest on the lower disc. To maintain the holder in driving engagement with the shaft 40, the shaft 40 is provided with ears 60 straddling a lever 62 pivoted between the ears and having an inturned end 64 engaging a circular groove 66 in the upper end of shaft 50. A spring 68, seated in recesses in the shaft 40 and lever 62, serves to maintain the end 64 of the lever in engagement with the groove.

The shaft 34 also drives two drum cams 70 and 72 fastened on the shaft, the cams each driving a lever 74 pivoted on a suitable fixed support 76, the free end of the lever driving a slide 78 carrying a knife 80 and slideable in a fixed way 82.

For each rotation of the shaft, the holder 49 will be indexed one step from where one vial is beneath the coil string to where the next vial is so located. Also for each index of the holder, the knives 80 will be brought together to sever a segment from the string and the segment will drop into the vial, the drum cams being so contoured as to effect a severing action on the string after the holder has been brought to rest.

When the vials in holder 49 have all been filled, the drive to the shaft 34 is discontinued and the lever 62 is manipulated to release the holder. Thereupon the holder with the vials therein is inserted into a vat for acid and rinse treatments of the coil segments 12 while a re-

placement holder, loaded with empty vials, is attached to the shaft 40.

After the coils have been freed of acid and properly washed, they may be dumped from each vial into an individual compartment 80 in a tray 82, ready for subsequent handling.

Although one embodiment of the invention has been shown and described, it will be apparent to those skilled in the art that various changes and modifications may be made therein without departing from the scope of the invention as defined by the appended claims.

What is claimed is:

1. In the method of manufacture of a coil of wire from a string of coiled wire provided with a coil supporting mandrel therein and which mandrel is soluble in acid, while the wire is not, the steps comprising cutting the string into individual coiled wire segments, depositing each segment as it is cut into a perforated container whose bottom supports the segment, one segment for each container, placing all of said containers in a common vat filled with an acid to dissolve the mandrel only, and subsequently washing the acid from the mandrelless segments.

2. In the method of manufacture of a coil of wire from a string of coiled wire provided with a coil supporting mandrel therein and which mandrel is soluble in an acid bath while the wire is not so soluble, the steps comprising cutting the string into individual coiled wire segments, depositing each segment as it is cut into a container having a perforation in the side wall thereof adjacent the bottom thereof, one segment for each container, placing all of said containers in a common vat

filled with an acid to dissolve the mandrel only, and subsequently washing the acid from the mandrelless segments.

3. In the method of manufacture of a coil of wire from a string of coiled tungsten provided with a coil supporting mandrel of molybdenum therein and which mandrel is soluble in acid, while the wire is not, the steps comprising cutting the string into individual coiled wire segments, depositing each segment as it is cut into perforated container whose bottom supports the segment, one segment for each container, placing all of said containers in a common vat filled with an acid to dissolve the mandrel only, and subsequently washing the acid from the mandrelless segments.

4. In the method of manufacture of a coil of wire from a string of coiled tungsten provided with a coil supporting mandrel of molybdenum therein and which mandrel is soluble in an acid bath and consisting essentially of 40% concentrated sulphuric acid, 40% concentrated nitric acid and 20% of water, while the wire is not, the steps comprising cutting the string into individual coiled wire segments, depositing each segment as it is cut into a perforated container whose bottom supports the segment, one segment for each container, placing all of said containers in a common vat filled with an acid to dissolve the mandrel only, and subsequently washing the acid from the mandrelless segments.
